PISTON RESIZING AND RESHAPING
MACHINE

Charles A. Marien and Melvin W. Marien, St. Louis, Mo., assignors to Ramsey Accessories Manufacturing Corporation, St. Louis, Mo., a corporation of Missouri

Application August 24, 1936, Serial No. 97,652

6 Claims. (Cl. 78—101)

Our invention has relation to improvements in machines for reshaping and enlarging pistons and it consists in the novel features of construction more fully set forth in the specification and 5 pointed out in the claims.

The present invention is an improvement over that shown in Patent No. 2,052,355, dated August 25, 1936, and like the invention of said patent has for its principal object the provision of a 10 machine for peening the inside of a piston skirt to reshape the same after it has become worn and misshapen from use so as to no longer properly fit the engine cylinder.

In addition to the objects of the patent aforesaid, the present invention has the further object of confining the piston to a cylindrical shape while undergoing a peening operation by a hammer provided for this purpose so as to insure a more satisfactory finished job without the necessity of expertise in the operator. This advantage will be better apparent from a more detailed description of the invention in connection with the accompanying drawings, in which:

Figure 1 is a side elevation of our improved machine with parts shown in section; Fig. 2 is a cross-sectional view taken on the line 2—2 of Fig. 1 showing the resizing sleeve and guides therefore in top plan; Fig. 3 is a front elevation, with parts in section, of the resizing sleeve for 20 confining the piston and at the same time serving as an anvil against which the hammer operates; Fig. 4 is a front elevation of the guides for the resizing sleeve, with parts in section; Fig. 5 is a top plan of said guides.

Referring to the drawings, our improved machine comprises a supporting standard 1 (preferably channel shaped) having a bottom flange 2 whereby the machine may be securely fixed by means of bolts 3, 3 to a table or bench 4 provided 30 with a supporting member 5. The side members 1, 1 of the standard 1 are separated by a space 8 throughout substantially the entire length except near the upper ends where they are connected by a transverse wall 9 which is projected forwardly beyond the members 1, 1, as shown at 9' (Fig. 1). At the upper end of the standard 1 a housing 10 is securely fixed, enclosing within it a substantially circular chamber 11, with which communicates an opening 12 extending forwardly 45 through the housing 10. A bracket 13 is carried by the standard 1, said bracket having a web 14 extending rearwardly and disposed in the space 8 in the members 1, 1. The web 14 is provided with a slot 15 and a bolt 16 passes 55 through suitable openings in the members 1, 1

and through the slot 15 to hold the bracket 13 firmly in place. An adjusting screw 17 traverses a tapped opening 18 in the rear wall 19 of standard 1 and bears against the web 14, whereby said web may be pushed outwardly by 5 an adjustment of said screw. Obviously, nut 16' on bolt 16 must be loosened before such an adjustment can be effected. The bracket is T-shaped and the outwardly presented head portion 20 thereof is substantially oval in cross-section and its top and bottom surfaces 21, 22 are provided with spaced tapped openings for cap screws 23, 23 and 24, 24 which hold upper guide arms 25, 25 and lower guide arms 26, 26 on the bracket head 20.

The inner adjacent ends of both pairs of guide arms are provided with gear teeth t, t arranged in mesh so that on the movement of one arm, the other will be correspondingly moved, whereby the arms will always be maintained in equal 20 angular relation with a vertical plane bisecting the bracket between screws 23, 23 and 24, 24 which serve as the pivots about which arms 25, 25 and 26, 26 rotate. The free ends of upper arms 25, 25 and lower arms 26, 26 are connected 25 by rollers 27, 27 and in between the rollers and pivotal screws are rods 28, 28. The upper ends of rods 28, 28 are provided with threaded stems 28', 28' and a link 29 fits over said stems 28', 28', one end of the link receiving stem 28' in an opening o and the other end of the link receiving the opposite stem 28' in a slot o'. Wing nuts n and n' are passed over the threaded stems 28', 28' and may be tightened to securely fasten the link 29 to the rods 28, 28, thereby rigidly holding 35 the rods in any desired spaced relation. When it is desired to change the adjustment of the rollers 27, 27, the nuts n, n' are loosened which permits movement of the arms 25, 25, after which the wing nuts n, n' are again securely fastened. 40 The arms 25 and 26, together with the rollers 27, 27 extending therebetween, serve as a guide or cradle for the support of a resizing sleeve 30 in which a piston P (which is being resized) is held. The resizing sleeve 30 is provided with an open 45 slot on opposite sides of which are lugs 32, 33. A screw 34 passes freely through an opening 35 in lug 32 and screws into tapped opening 36 in lug 33. A second screw 37 passes through a tapped opening 38 in lug 33 and is adapted to 50 bear against the inner surface 39 of lug 32.

It will be apparent that the screws 34 and 37 act oppositely in that the slot 31 may be drawn together by means of the screw 34 and the sleeve thereby made somewhat smaller, while the said 55

slot may be forced apart by the screw 37 and the sleeve thereby made somewhat larger. In order to preserve as nearly as possible the cylindrical shape of the inner surface 48 of the resizing sleeve 30, the cross section of the sleeve is eccentrically formed with the thinner wall section immediately adjacent the slot 31 and the thicker wall section directly opposite to the said slot. By thus forming the sleeve it will maintain a substantially cylindrical shape while the slot 31 is being expanded. The advantage of maintaining the cylindrical shape of the inner surface of the sleeve throughout the various adjustments to which the sleeve is subjected will be better apparent from the description of the operation of the invention set forth below. A hammer 41, having a head 42 formed on its lower end, is mounted on a pivot 43 within housing 10 and has a short lever arm 44 projecting inwardly at approximately a right angle so that the hammer is substantially in the form of a bell crank. A rotary cam wheel 45 engages with the short arm 44 and when said cam is rapidly rotated through suitable connections with the motor 46, the hammer shank will be repeatedly lifted and forcibly pulled downwardly by a spring 47 connected to it and to a lever 48 mounted on a lug 49 projecting rearwardly from the standard 1. The action of the hammer 41 is controlled by the pedals 50 and 51 in identically the same manner as in said patent aforesaid No. 2,052,355. Since no claims are made to this specific mechanism, a detailed description thereof is not deemed necessary.

In order to insure that the piston P will not move within the resizing sleeve 30, a set screw 52 is inserted into a tapped opening 53 in the sleeve 30 near lug 32 and may be screwed inwardly to bear against the piston surface and thereby hold the same against turning during the peening operation.

On the average, when pistons require replacement or expanding, the cylinder wear approximates .005 inch. For this reason the resizing sleeve 30 is made .005 inch oversize with the slot 31 its normal width of about one-sixteenth of an inch. Now the worn piston that is to be reshaped within the sleeve 30 is generally from .005 inch to .010 inch smaller than the sleeve. Therefore, the operator, after inserting the piston in the sleeve, adjusts the screws 34 and 37 so as to contract the slot 31 to make the sleeve just sufficiently small to firmly hold the piston within it. Since most of the peening is to be done adjacent to the slot S of the piston P, the piston is inserted in the sleeve 30 with its slot S opposite the slot 31 of the sleeve. The operator now holds the sleeve 30 against the rollers 21, 21 and causes the hammer head 42 to strike rapidly on the inner surface of the piston P at such points as he desires, the piston P being moved, together with the resizing sleeve 30, to effect control of the peening action.

In slotted pistons the portions of the piston skirt adjacent to the slot collapse causing considerable reduction in the diameter of the piston 65 at right angles to the axis of the pin bosses. This is corrected by peening the inner surface of the piston skirt along vertical lines adjacent to the piston slot.

Obviously, the more the inner surface of the piston is peened, the greater are the strains set up in the metal to which the metal can not respond owing to the confinement of the piston within the resizing sleeve 30. The confinement of the piston by the sleeve causes these internal 75 strains to be distributed over a considerable area

and also insures the retention of the cylindrical shape of the piston. However, when the sleeve 30 is expanded by the manipulation of the screws 34 and 37 and the piston is removed from the sleeve, the piston will immediately expand in response to the tension set up in the piston wall by the peening operation. The degree of expansion of the piston, of course, is dependent upon the amount of peening that is performed on the inner surface of the piston. This is under the control of the operator. Obviously, if a piston is very much undersized, the operator will adjust the screws 34 and 37 to enlarge the sleeve 30 during the peening operation. That is, after performing a certain amount of peening, the sleeve 30 is expanded, after which further peening is performed until the operator is satisfied that the piston has been enlarged a sufficient amount to properly fit the cylinder in which it is intended to operate.

If desired, the operator may impart a cam shape to a piston. That is, by directing the peening along certain lines adjacent to the slot of the piston, he can cause the diameter at right angles to the axis of the pin bosses to increase so that it will be greater than the diameter parallel with the pin bosses.

The confinement of the piston within the sleeve makes any delicate control of the peening operation unnecessary since, as stated above, the sleeve causes the strains in the metal to be distributed over a greater area than if there were no such confinement but merely peening against an anvil.

Having described our invention, we claim:

1. A machine for reshaping pistons, including a hammer for insertion into a piston, a resizing sleeve for holding a piston in the path of the hammer, means for supporting said sleeve, said supporting means permitting free longitudinal movement and rotation on the longitudinal axis of the sleeve relative to the hammer, and means for rapidly reciprocating the hammer against the piston wall.

2. A machine for reshaping pistons, including a hammer for insertion into a piston, a resizing sleeve for holding a piston in the path of the hammer, means for contracting and expanding said sleeve, means for supporting said sleeve, said supporting means permitting free longitudinal movement and rotation on the longitudinal axis of the sleeve, relative to the hammer, and means for rapidly reciprocating the hammer against the piston wall.

3. In a machine for reshaping pistons, a resizing sleeve for receiving the piston, the inner surface of said sleeve being cylindrical and eccentric with respect to the outer surface, the wall of said sleeve being longitudinally slotted at its thinnest portion, and means for increasing or decreasing the size of the sleeve.

4. A machine for reshaping pistons, including a hammer for insertion into a piston, a resizing sleeve for holding a piston in the path of the hammer, means for rapidly reciprocating the hammer against the piston wall, means for supporting said sleeve, said supporting means comprising oppositely disposed movable cradle members, cooperating means on said cradle members whereby said members are movable in unison, and means for locking said cradle members in fixed relation.

5. A machine for reshaping pistons, including a hammer for insertion into a piston, a resizing sleeve for holding a piston in the path of the hammer, means for rapidly reciprocating the hammer against the piston wall, means for supporting said

sleeve, said supporting means comprising oppositely disposed movable cradle members, rollers at the outer ends of the cradle members for receiving the resizing sleeve, suitable gearing connecting the cradle members whereby they are movable in unison, and means for locking the cradle members in fixed relation.

6. A machine for reshaping pistons, including a hammer for insertion into a piston, a resizing

sleeve for holding a piston in the path of the hammer, means for rapidly reciprocating the hammer against the piston wall, and oppositely disposed supporting members for supporting the sleeve, whereby the hammer will strike the piston wall 5 along a line between said supporting members.
